UNITED STATES PATENT OFFICE.

JAMES H. OTTO, OF BEELER, IDAHO.

COMBINATION BELT-LOOP AND BUTTON.

1,315,856.

Specification of Letters Patent.

Patented Sept. 9, 1919.

Application filed March 8, 1918. Serial No. 221,173.

To all whom it may concern:

Be it known that I, JAMES H. OTTO, a citizen of the United States, residing at Beeler, in the county of Shoshone and State of Idaho, have invented certain new and useful Improvements in Combination Belt-Loops and Buttons; and I do hereby declare the following to be a full, clear, and exact description of the invention, such as will enable others skilled in the art to which it appertains to make and use the same.

This invention relates to trouser attachments and the primary object of the invention is to provide an improved trouser attachment or fastener having a two-fold function of receiving the belt and suspenders for holding the same in position.

Another object of the invention is to provide an improved trouser attachment for receiving the belt and suspender formed of a single piece of wire having retaining prongs formed thereon whereby the same can be readily and quickly secured to the trousers without necessitating the employment of needle and thread.

A further object of the invention is to provide an improved trouser attachment comprising an attaching base and a downwardly extending inwardly bent spring hook forming a loop for receiving the belt and a means for receiving and holding the suspenders.

A still further object of the invention is to provide an improved trouser attachment of the above character, which is durable and efficient in use, one that is simple and easy to manufacture, and one that can be placed upon the market at a reasonable cost.

With these and other objects in view the invention consists in the novel construction, arrangement and formation of parts, as will be hereinafter more specifically described, claimed and illustrated in the accompanying drawing forming a part thereof, in which:

Figure 1 is an elevation of the improved device attached to the trousers showing the same used as a loop for supporting a belt,

Fig. 2 is a similar view showing the same used for a hook for receiving the suspender tabs.

Fig. 3 is a side elevation of the attachment showing the same in position on a pair of trousers with a belt in position thereon,

Fig. 4 is a similar view showing the suspender tabs in position thereon, and

Fig. 5 is a detail perspective view of the

improved attachment removed from the trousers.

Referring to the drawing in detail where-in similar reference numerals designate corresponding parts throughout the several views, the numeral 1 generally indicates the improved attachment which is adapted to be secured to a pair of trousers 2. The attachment 1 is adapted to be secured at spaced intervals around the upper edge of the trousers and is arranged to supplement the ordinary belt loops and buttons usually secured around the trousers tops. This attachment is so formed that when a button or belt loop is torn from the trousers, the retaining prongs, which hereinafter will be more fully described, can be readily inserted in the trousers and bent in position and the removal of the same is practically impossible.

The improved trousers attachment 1 is formed from a single length of wire bent back upon itself at the central portion thereof of providing a vertical body portion 3 of double thickness. The body portion 3 is bent rearwardly as at 4 toward the trousers 2 and then downwardly to provide a trouser engaging portion 5, which lies in spaced parallel relation to the body portion 4. The ends of the wire are bent outwardly in opposite directions at approximately the central portion of the body engaging portion 5 as at 6 to provide legs 7 so as to form a relatively wide base to engage the trousers 2, and the legs 7 lie in the same plane as the trousers engaging portion 5. The terminals of the legs 7 are bent inwardly as at 8 and then upwardly as at 9 and sharpened as at 10 to provide retaining prongs for engaging the cloth of the trousers and prevent displacement thereof. The upwardly bent portions 9 are arranged to engage the rear face of the trousers and are adapted to be bent slightly inward so as to firmly clamp the cloth between the body portion 3, the legs 7, and the bent portion 9 of the retaining prongs. The free end of the body portion 3 is bent inwardly toward the trousers as at 11 and slightly upwardly as at 12 to provide a hook portion to prevent the removal of any article placed between the body portion 3 and the trousers. The hook portion 12 is formed relatively wide as at 13 to provide an enlarged bearing portion to engage the article positioned between the body portion 3 and the legs 7. The strands of the

100
105
110

wire forming the hook portion 12 are spaced from each other at this point to provide the enlarged portion.

In operation of the improved device the retaining prongs are forced through the cloth of the trousers and are then bent upwardly and inwardly as described above and as shown in Figs. 1 and 3 a belt 14 can be readily placed between the body portion 3 and the trousers engaging portion 5 and legs 7 and held against displacement. The belt 14 can be either threaded in between the body portion 3 and the trousers, or the same can be placed between the same by springing the body portion 3 and hook 12 outwardly and sliding the belt in between the ends of the hook and the trousers. As shown in Figs. 2 and 4, a suspender tab 15 is shown in position and in this arrangement the hook portion 12 is placed in the button holes of the suspender tab and the same is slid upwardly to engage the curved portion 4 thereof. The hook portion 12 is arranged to lie intermediate the legs 7 and relatively near the trousers, so as to prevent the displacement of the belt and suspender tab.

From the foregoing description, it can be seen that an improved attachment for trousers is provided which serves a two fold purpose, namely of receiving and supporting a trousers belt and for holding the suspender tabs in position. The formation of the attachment also allows the same to be readily and quickly applied to a pair of trousers without employing needle and thread.

In practice, I have found that the form

of my invention, illustrated in the accompanying drawings and referred to in the above description, as the preferred embodiment, is the most efficient and practical; yet realizing the conditions concurrent with the adoption of my device will necessarily vary, I desire to emphasize the fact that various minor changes in details of construction, proportion and arrangement of parts may be resorted to, when required without sacrificing any of the advantages of my invention as set forth.

What I claim as new is:—

An attachment for trousers and the like formed of a single length of wire bent intermediate its ends and comprising a vertical body portion, a spaced parallel trouser engaging portion having the free end thereof provided with outwardly and oppositely extending legs for forming a relatively flat wide bearing member, inwardly and angularly extending retaining prongs formed on the legs and extending in spaced parallel relation to the legs for engaging the cloth, the body portion having its free end bent inwardly and angularly toward the trousers and in close proximity thereto to provide a closed loop, said bent end being arranged intermediate the prongs, as and for the purpose specified.

In testimony whereof I affix my signature in presence of two witnesses.

JAMES H. OTTO.
